UNITED STATES PATENT OFFICE.

WLADYSLAW GIERACKI, OF AVON, CONNECTICUT.

LIFE-SAVING SUIT.

1,253,370.

Specification of Letters Patent. Patented Jan. 15, 1918.

Application filed October 16, 1917. Serial No. 196,907.

To all whom it may concern:

Be it known that I, WLADYSLAW GIERACKI, a citizen of Russia, residing at Avon, in the county of Hartford and State of Connecticut, have invented certain new and useful Improvements in Life-Saving Suits, of which the following is a specification.

This invention relates to certain new and useful improvements in life saving suits.

10 The primary object of the invention is the provision of a suit adapted to be worn by a person without inconvenience and provided with an inflatable means for maintaining the wearer in a floating position upon the water, ready means being arranged for deflating the device.

20 A further object of the invention is to provide a life preserver in the nature of a pneumatic life belt furnished with a plurality of air tight portions readily inflated when desired and easily and readily deflated simultaneously.

25 A still further object of the device is to provide a suit having an inflatable belt portion serving as a float and so arranged that a puncturing of one portion thereof will not cause a deflation of the remainder of the float member.

30 In the drawings forming a part of this application and in which like designating characters refer to corresponding parts throughout the several views.

Figure 1 is a perspective view of the complete device.

35 Fig. 2 is a vertical sectional view of a portion thereof,

Fig. 3 is an elevational view of a side portion of the same partly broken away,

40 Fig. 4 is a horizontal sectional view taken through the float member with a portion of the device shown in plan.

Fig. 5 is a detail sectional view of one of the air releasing valves, in its closed arrangement and

45 Fig. 6 is a view thereof in its open position.

My invention broadly comprises an inflatable life belt 10 having a plurality of compartments 11, the said belt being adapted to 50 be worn by a person, one manner of attaching the belt to the person being herein illustrated in the form of a suit 12 having legs 13, opposite body inclosing portions 14 and securing straps or neck bands 15.

55 The belt 10 which is sewed into the suit 12 at the waist line thereof consists of an in-

flatable tube 16 preferably formed of rubber and having an inflating conduit 17 leading thereto. The compartments 11 are formed by means of transverse partitions 18 60 provided in the tube 16 while the inflating conduit 17 communicates with each compartment 11, through a valve inlet 19.

An inflating nipple 20 is provided for the conduit 17 whereby all of the compartments 65 11 may be simultaneously inflated through the inlet valves 19 thereof. An outlet valve 21 is provided for each compartment 11 opening into a metallic conducting pipe 22 furnished with a plurality of vents or openings 23. Simultaneous releasing means for the valves 21 is provided in the form of a wire 24 shiftably longitudinally arranged within the pipe 22 and having a ball or shoulder 25 positioned adjacent each of the 70 valves 21. The free ends of the wire 24 project outwardly of the pipe 22 being arranged with knobs or handles 26 and 27 upon their free ends and whereby the wire 24 may be moved longitudinally in either 75 direction desired.

The balls 25 are so arranged with respect to the plungers 28 of the valves 21 as to be positioned normally out of contact with said plungers as shown in Fig. 5 of the drawings 80 when the end of the wire 24 which is provided with the knob 26 is outwardly withdrawn to its greatest extent, the wire 24 being at such times at the limit of its movement in one direction. Upon pulling the knob 27, 85 the wire 24 is shifted longitudinally for positioning the balls 25 within the adjacent socketed ends 29 of the valve plungers 28 as illustrated in Fig. 6 and thereby simultaneously opening all of the valves 21 permitting air to quickly escape from the compartments 11 into the pipe 22 and through the ports 23 to the atmosphere.

It will be understood that the knobs 26 and 27 prevent the free ends of the wire 24 from 90 entering the pipe 22 as well as serving for readily moving the wire 24 for releasing the valves 21 as described and also for permitting the said valves to return to their closed positions upon pulling the knob 26. A 95 serviceable life belt is arranged which may be attached to the person in any desired manner and which will not become deflated upon being punctured at any single point, as the unpunctured compartments 11 will be maintained inflated although air may be readily released from all of the compartments 11 100 105 110

when desired by means of the knob 27. The suit 12 may be worn whenever desired and the belt 10 inflated and deflated whenever found desirable.

5. What I claim as new is:—

1. A life belt comprising an air-tight tube, transverse partitions within the tube forming non-communicating compartments, valved inflating means for said compartments, normally closed outlet valves individually arranged for the compartments, a pipe carried by the tube into which said outlet valves exhaust arranged with outlet ports, a wire longitudinally arranged shiftable within the 10 said pipe having outwardly projecting free ends, handles upon said ends exteriorly of the pipe, balls upon the wire adjacent the outlet valves adapted for opening reception adjacent each of the said valves upon longitudinal shifting of the wire in one direction.
- 15

2. A life belt comprising an air-tight tube, transverse partitions within the tube forming non-communicating compartments, valved inflating means for said compartments, normally closed outlet valves individually arranged for the compartments, a pipe carried by the tube into which said outlet valves exhaust arranged with outlet ports, a wire longitudinally arranged shiftable within the 20 said pipe having outwardly projecting free ends, handles upon said ends exteriorly of the pipe, balls upon the wire adjacent the outlet valves adapted for opening reception adjacent each of the said valves upon longitudinal shifting of the wire in one direction, 25 under the influence of one of said knobs and adapted for release from said outlet valves under the influence of the other knob.

In testimony whereof I affix my signature.
WLADYSLAW GIERACKI.
